**1-FARNESYLACETYL-4-HYDROXYALKYL-
PIPERAZINES**

Ivar Laos, Skokie, Ill., assignor to G. D. Searle & Co.,
Chicago, Ill.

ABSTRACT OF THE DISCLOSURE

N-substituted farnesylacetyl piperazines are prepared by acylation of an N-substituted piperazine with a farnesylacetyl halide. These amides exhibit valuable pharmacological properties, e.g. anti-ulcerogenic, anti-bradykinin, antiprotozoal and anthelmintic.

The present invention is concerned with novel derivatives of farnesylacetic acid and, more particularly, with 1-farnesylacetyl-4-hydroxyalkyl-piperazines as represented by the following structural formula

wherein Alk represents a lower alkylene radical possessing at least two carbon atoms.

The lower alkylene radicals depicted by Alk in the foregoing structural formula are typified by ethylene, trimethylene, tetramethylene, pentamethylene and the branched chain groups isomeric therewith.

Farnesylacetic acid halides are conveniently utilized as starting materials for the manufacture of the compounds of this invention. Reaction with the N-hydroxyalkylpiperazine is readily carried out at low temperature. A particularly useful acid halide is farnesylacetyl chloride, described by Cardani et al., J. Med. Chem., 6, 457 (1963). Reaction of farnesylacetyl chloride with N-(2-hydroxyethyl)piperazine, for example, thus affords 1-farnesylacetyl-4-(2-hydroxyethyl)piperazine.

Equivalent to the amines of this invention are the corresponding non-toxic acid-addition and quaternary salts thereof as exemplified by the citrate, maleate, ascorbate, tartrate, succinate, oxalate, lactate, glycolate, gluconate, benzoate, cinnamate, nitrate, hydrochloride, hydrobromide, phosphate, methochloride, methobromide, ethochloride, ethobromide, etc.

The compounds of this invention are useful as a result of their valuable pharmacological properties. They are, for example, anti-ulcerogenic agents as is evidenced by their capacity to inhibit ulcer formation in the Shay rat as reported by Shay et al., Gastroenterology, 5, 43 (1943). Details of the assay utilized to detect that activity are contained in U.S. Pat. 3,483,192, issued Dec. 9, 1969. These compounds are also antiprotozoal agents in view of their ability to inhibit the growth of organisms such as *Tritrichomonas foetus* and anthelmintic agents as is evidenced by their immobilizing action against nematodes such as *Turbatrix aceti*. The assays used to detect those antiprotozoal and anthelmintic activities are described in detail also in the aforementioned U.S. Pat. 3,483,192, issued Dec. 9, 1969.

The compounds in this invention possess, in addition, anti-spasmodic activity as demonstrated by their ability to inhibit bradykinin-induced contractions. Details of the assay used for detection of that activity are as follows:

Two Charles River female rats weighing 240-280 grams are treated on each of two successive days with diethylstilbestrol in order to induce a state of estrus. On the third day the animals are sacrificed and the uteri are removed. A 10 mm. section is taken from one of the uteri

2

and suspended in a tissue bath containing 1.9 ml. of Tyrode's solution, prepared as described by Barnes and Eltherington, "Drug Dosage in Laboratory Animals," p. 261, University of California Press, Berkeley, Calif. (1964). The tissue bath is surrounded by a water jacket maintained at a constant temperature of 30° C. The concentration of bradykinin in the tissue bath is then gradually increased by successive additions of bradykinin dissolved in Tyrode's solution. The bradykinin solution is defined in the pD, which is the log of the reciprocal of the concentration expressed in mg./ml. At each of the selected bradykinin concentrations, contraction of the uterus is measured in mm. by means of an E & M Physiograph used together with an Isotonic Myograph Transducer and Detecting Head. After completion of those measurements the tissue is rinsed nine times over a period of 9 minutes with fresh Tyrode's solution. The last rinse is kept in the bath and 100 mcg. of the test compound dissolved or suspended in 0.1 ml. of Tyrode's solution is injected into the bath, which consists of 1.9 ml. of Tyrode's solution. After 10 minutes the bradykinin concentration in the bath is again increased as before by the successive additions of bradykinin dissolved in Tyrode's solution. The contractions at each concentration are measured as before and are compared with the control values, i.e. those obtained in the absence of the test compound. The identical procedure is then carried out with the 10 mm. section of the uterus taken from the second animal. A compound is considered active either if it inhibits by at least 10% the maximum bradykinin-induced contraction or if it causes an increase of at least 0.3 pD unit in bradykinin concentration required to effect 50% of the maximum concentration.

The invention will appear more fully from the examples which follow. These examples are set forth by way of illustration only and it will be understood that the invention is not to be construed as limited thereby either in spirit or in scope as many modifications both in materials and in methods will be apparent from this disclosure to those skilled in the art. In these examples temperatures are given in degrees centigrade (0° C.) and quantities of materials in parts by weight unless otherwise noted.

EXAMPLE 1

To a solution containing 2.73 parts of N-(2-hydroxyethyl)piperazine in 228 parts of butanone, under nitrogen is added dropwise at 0-5° with stirring over a period of about 10 minutes a solution of 2.83 parts of farnesylacetyl chloride dissolved in 12 parts of butanone. After completion of the addition the reaction mixture is allowed to warm to room temperature, then is heated at the reflux temperature for about 1 hour. At the end of that reaction period, the mixture is cooled and the insoluble material removed by filtration. Removal of the solvent by distillation under reduced pressure affords an oily residue, which is dissolved in benzene. The resulting organic solution is washed with water until neutral. That solution is dried over anhydrous sodium sulfate and distilled to dryness to afford 1-farnesylacetyl-4-(2-hydroxyethyl)-piperazine.

The latter amine is dissolved in 140 parts of anhydrous ether and is stirred while 1.5 parts by volume of an isopropanolic hydrogen chloride solution diluted with 70 parts of anhydrous ether is added. The latter solution contains one molecular equivalent of hydrogen chloride. The resulting amine hydrochloride is collected by filtration, then purified by dissolution in isopropyl alcohol followed by precipitation with ether. The resulting precipitate is collected by centrifugation to afford 1-farnesylacetyl-4-(2-hydroxyethyl)piperazine hydrochloride. This compound displays nuclear magnetic resonance maxima, in deuteriochloroform, at about 98, 102, 120, 142, 200, 242 308 and

3

365 cycles per second and is represented by the following structural formula

EXAMPLE 2

When a solution containing 4.25 parts of farnesylacetyl chloride in 20 parts of butanone is allowed to react with a solution containing 4.54 parts of N-(2-hydroxypropyl) piperazine dissolved in 36 parts of butanone according to the procedure described in Example 1, there are obtained 1-farnesylacetyl - 4 - (2-hydroxypropyl)piperazine and the corresponding hydrochloride.

EXAMPLE 3

The reaction of a solution of 4.25 parts of farnesylacetyl chloride dissolved in 20 parts of butanone with a solution containing 4.16 parts of N-(3-hydroxypropyl) piperazine in 36 parts of butanone according to the procedure described in Example 1 results in 1-farnesylacetyl-4-(3-hydroxypropyl)piperazine and the corresponding hydrochloride.

What is claimed is:

1. A compound of the formula

wherein Alk is a lower alkylene group possessing two to seven carbon atoms.

2. As in claim 1, a compound of the formula

4

wherein Alk is a lower alkylene group possessing either two or three carbon atoms.

3. As in claim 1, a compound of the formula

10 wherein n is either 2 or 3.

4. As in claim 1, the compound which is 1-farnesyl-acetyl-4-(2-hydroxyethyl)piperazine.

5. As in claim 1, the compound which is 1-farnesyl-acetyl-4-(2-hydroxypropyl)piperazine.

15 6. As in claim 1, the compound which is 1-farnesyl-acetyl-4-(3-hydroxypropyl)piperazine.
